UNITED STATES PATENT OFFICE.

LINCOLN A. THORNBURG, OF MUNCIE, INDIANA, ASSIGNOR TO WINDOW GLASS MACHINE COMPANY, OF PITTSBURGH, PENNSYLVANIA, A CORPORATION OF NEW JERSEY.

GLASS-DRAWING APPARATUS.

1,124,823.

Specification of Letters Patent. Patented Jan. 12, 1915.

Application filed June 17, 1911. Serial No. 633,647.

To all whom it may concern:

Be it known that I, LINCOLN A. THORNBURG, a resident of Muncie, in the county of Delaware and State of Indiana, have invented a new and useful Improvement in Glass-Drawing Apparatus, of which the following is a full, clear, and exact description, reference being had to the accompanying drawings, forming part of this specification, in which—

Figure 1 is a vertical transverse section of my improved apparatus; Fig. 2 is a side elevation of the same.

My invention relates to the drawing of glass from pots or receptacles, and its object is to provide an improved pot system which may be used either in single or double form.

In the drawings, in which I show a preferred form of my apparatus, 2 represents a double pot bottom, preferably circular in form, and having projecting rims 3, on opposite sides, with projecting integral trunnions 4, 4, which are preferably angular in cross section at their outer ends. The intermediate portions 5 of the trunnions are preferably circular where they project through vertical slots in the side walls 6, 6, of the furnace chamber. The furnace 7 may be of any desirable form, for example, square in cross section with outer steel or iron plates 8, inclosing the brick or other refractory lining 9.

The topstone 10 has a large central hole with a depending circular ring 11, these parts being preferably formed in one integral piece of clay. The opening is preferably circular in form. The ring 11 and the rims of the pot bottom are preferably so related that the rims fit neatly and closely about the depending ring to make a close joint and to cut off the hot currents from the drawing point. The depending flange or ring 11 is preferably so constructed that when in operative relation to the pot bottom 2, the lower edge of said flange will fit against the upper surface of said bottom within the rims 3.

Shields 12 are preferably placed on the cylindrical trunnions between the slotted refractory lining and the slotted furnace plates, these shields having holes to fit the cylindrical trunnions. The polygonal end portions of the trunnions fit within corresponding sockets 13, secured to metal trun-

nions 14, which rest within vertically slotted 55 bearings 15 of vertically sliding supports or standards 16. The bearings 15 are preferably forked and between the forks are secured pinions 17, these pinions engaging short racks 18, which slide within the bottom of the forked portion and are actuated by suitable connections, such as links 19, pivotally connected with levers 20, secured to a common shaft 21. The construction of the operating mechanism is the same at 65 both sides and a single hand lever 22 may be used to rock the shaft and turn the pot on its trunnions.

The vertical standards 16 extend through suitable guideways 23, and at the lower end 70 are connected by short links 24 with levers 25, pivoted to the sides of the furnace at 26. The links 24 are formed in two parts with a turn buckle connection between them, so that by turning the nut, the link may be 75 varied in length, thus adjusting one side relative to the other, so that the pot will fit horizontally against the sealing joint of the ring. The levers 25 are provided at their ends with segmental racks 27, engaging the 80 segmental pinions 28, on a common shaft 29, which is rocked by a suitable hand lever 30. By rocking this lever, the pot may be raised and lowered within the furnace chamber.

85 The handle has a spring-pressed catch 31, which engages teeth on a fixed segment, so that the pot may be locked in any desired position.

90 Into the well below the furnace projects a number of gas jets 32, adapted to melt the glass from the bottom face of the reversible bottom.

In order to take the weight of the shields off the pot trunnions, I preferably provide vertical supports 33, on the bearings, to which are adjustably secured hooked rods 34, engaging eye-bolts 35, secured to the tops of the shields.

100 In using the apparatus, the bottom is raised into the position shown in Fig. 1, the molten glass is ladled or otherwise fed into the ring of the topstone and rests on the top face of the bottom. The drawing is then carried out in the usual way, and when completed, the pot bottom is lowered, then turned over, and then again raised to its upper position with the other rim fitting neatly

around the depending ring of the topstone. Another portion of glass is then fed in and during the next drawing, the glass remaining on the bottom face is melted off by the 5 gas jets or by hot products of a regenerative furnace.

The advantages of my invention result from the use of a turning pot bottom in connection with the separate ring against which 10 the bottom fits.

The pot bottom may be of single form, that is, with only one receiving bottom face; the rim on the bottom may fit against the bottom of the depending ring, and other 15 changes may be made without departing from my invention.

I claim:

1. The combination with a rotatable glass pot having a rim, of a topstone having a 20 depending flange which fits within said rim and extends to the bottom of the pot cavity, substantially as described.

2. The combination with a rotatable glass pot having a rim, of a topstone having a 25 depending flange which fits within said rim, together with leveling means for the pot to adjust it to properly receive said flange, substantially as described.

3. The combination with a rotatable glass 30 pot having a rim, of a topstone having a depending flange which fits within said rim and extends to the bottom of the pot cavity, together with means for vertically separating the pot and topstone, substantially as 35 described.

4. The combination with a rotary reversible pot, having a rimmed pot cavity in both its upper and lower surfaces, of a topstone having a depending flange adapted to fit within either of said rims and form the 40 inner wall of the pot cavity, substantially as described.

5. The combination with a glass pot bottom and a mounting arranged to permit vertical movement of said bottom, said bottom 45 having a relatively shallow pot forming cavity therein, of a topstone having a depending flange adapted to fit within said pot cavity and form the sides of the pot; substantially as described. 50

6. The combination with a pot bottom mounted for rotary and also for vertical movement, and having a relatively shallow pot forming cavity in both its upper and its lower surface, said cavities being surrounded by a shallow rim, of a topstone having a depending flange adapted to fit within either of said rims, and to coöperate with the pot bottom to form a complete pot in either of the reversed positions of said 60 bottom; substantially as described.

In testimony whereof, I have hereunto set my hand.

Lincoln A. X. Thornburg.
His mark.
